AUTOMATIC WELL FLOWING DEVICE

Filed Nov. 15, 1927

UNITED STATES PATENT OFFICE

ALEXANDER BOYNTON, OF SAN ANTONIO, TEXAS

AUTOMATIC WELL-FLOWING DEVICE

Application filed November 15, 1927. Serial No. 233,499.

This invention relates to improvements in automatic stage lifts or well flowing apparatus, and it consists in the constructions, combinations and arrangements herein described and claimed.

An object of this invention, as well as of the invention in co-pending application for patent filed June 1, 1927, Serial No. 195,739, is to provide a valve apparatus for controlling the introduction of pressure fluid into a column of liquid desired to be raised so that the latter may be set in motion and elevated toward the surface.

A further object of the invention is to utilize the velocity of the upwardly moving liquid column for the regulation of the admission of the pressure fluid by which the lifting energy is supplied.

Other objects and advantages appear in the following specification, reference being had to the accompanying drawings in which:

Figure 1 is a longitudinal section of the improved valve apparatus,

Figure 2 is a cross section taken on the line 25 2—2 of Figure 1,

Figure 3 is a cross section taken on the line 3—3 of Figure 1,

Figure 4 is a detail perspective view of the so-called by-passing plunger or valve element referred to later.

In carrying out the invention, provision is made of a cylindrical shell or valve body 5 into the opposite extremities of which coupling heads or bushings 6 and 7 are screwed or otherwise fastened. Each bushing has provision for the the reception of adjoining sections 9 of the tubing string in which the valve apparatus is connected. The upper bushing acts as a stop and the lower bushing as a rest 40 for a hollow weight.

The reader may imagine the valve apparatus as being suspended in the casing of a well by means of the foregoing tubing string. It must also be supposed that the well casing 45 (not shown) contains fluid (air or gas) under pressure. This constitutes the pressure fluid hereinafter referred to, by which the liquid of the well is elevated.

Located within the valve body at one side 50 is an enlargement or valve casing 10 with a

longitudinal bore 11 communicating with inlet and outlet ports 12 and 13 for the upper and lower ends respectively, the latter port being formed in a bushing 13a screwed or otherwise secured in the upper extremity of 55 the bore. A bevel 14 at the innermost end of the port 13 provides a valve seat with which the plunger or valve element 15 may engage when lifted by the pressure of fluid by-passing it in the bore 11 to the point of egress at 60 the port 13.

A stem 16, comprising an extension of the plunger or valve element 15, is movable in the bushing 13a when the plunger is movable in the bore 11, the foregoing movement being 65 a matter under the control of the so-called revamping tube or nipple 17. This tube comprises a hollow weight which is loose in the shell. The inlet end of the tube is decidedly flared at 18 to produce a liquid expansion 70 chamber, the remaining and major internal portion of the tube being cylindrical. The opposite end (upper end in this instance) carries a flange or piston 19.

There is a slight distance between the extremity of the valve stem 16 and piston 19 thus permitting slight opening of the valve element 15, so that pressure fluid may enter the well tubing during times of slight differentials of pressures inside and outside of the 80 tubing. This accomplishment obtains while the revamping tube or nipple remains in resting position upon the lower bushing 7. Of necessity, the revamping tube and piston have easy working fits within the valve body, 85 enough clearance being provided to insure the desired easy movement even should sand particles or the like get between the working surfaces. The foregoing looseness in respect to the piston 19 is also essential for the free 90 passage of the pressure fluid around the edge of the piston and into the well tubing.

The bores 8 of the bushings 6 and 7 form part of the liquid conduit, it being observed that the diameter of the bores is the same as the internal diameter of the adjacent tube sections 9 and the internal diameter of the revamping tube 17. That portion of the bore 8 in the bushing 7 adjoining the flared end 18 of the revamping tube is enlarged, flared, 100

or laterally curved at 20 which, with the frusto-conical flare 18 of the tube, completes the liquid expansion chamber previously alluded to.

5 Ordinarily it may be supposed that the weight of the tube 17 and the carried piston 18 would be sufficient to insure the gravitation of the revamping element to a seating position upon the bushing 7. While this result obtains in practice, yet it is preferred to make sure of the action by the addition of a light coil spring 21. This coil spring is interposed between the piston 19 and the shoulder 22 of a narrow chamber 23 formed by cutting 15 away a portion of the bushing 6.

The effect of the spring is to resist the upward movement of the revamping element as the pressure differential increases, or in other words, as the velocity of the liquid column increases, and to accelerate the down movement thereof as the differentials of pressures tend to equalize, due to a slowing down of the foregoing movement of the liquid column. The spring compensates for a lack of weight of 25 the revamping element. It may be added that varying compression stresses of the spring may very properly be used to obtain working adjustments which the dead weight of the revamping element would not properly 30 afford even if such dead weight could be increased or decreased at will.

The difference between the diameters of the plunger and plunger chambers should vary from .005" to .025". The diameter of the 35 spring 21 should be from $\frac{5}{8}$ " to $\frac{1}{4}$ " and should be wrapped in proper pitch to produce sealing-off engagement of plunger upon its upper seat at a differential pressure varying from 50 lbs. to 100 lbs. per square inch.

40 The devices should be so spaced in the tubing string that the weight of fluid in the tubing between adjacent devices is from one-fourth to one-half as much as the pressure per square inch required to compress the spring and thereby force the plunger to sealing-off engagement upon its upper seat. For illustration, assume the weight of the fluid between any two adjacent devices to be 30 lbs. per square inch, then the pressure per 45 square inch required to compress the spring and seal-off the plunger upon its upper seat should be 60 lbs. to 120 lbs.

The above spacing gives the best results and states the spacing rule correctly, but flow 50 will be initiated and maintained if the weight of the fluid per square inch between the valves is only slightly less than the pressure per square inch required to compress the spring sufficiently to cause the plunger to seal-off 55 upon its upper seat. For illustration, assume the weight of the fluid between any two adjacent devices to be 30 lbs. per square inch, then the pressure per square inch required to compress the spring until the plunger 60 seals-off upon its upper seat must be slightly

over 30 lbs. and should, as first stated, be from 60 lbs. to 120 lbs.

The operation may be readily understood. The valve apparatus pictured in Figure 1 is suspended in the casing of a well (not shown) by virtue of being carried in the tubing string partly indicated by the adjacent sections 9. The reader may suppose the well casing to contain fluid (air or gas) under a predetermined pressure. According to the principles announced in preceding patent applications, the pressure fluid is admitted to the well tubing for the purpose of moving a column of liquid upwardly in the well tubing. The valve apparatus now under 70 consideration constitutes the automatic control of the admission of the pressure fluid.

75 It is easy to understand that an appropriate velocity of the moving liquid column will hold the so-called revamping element 17 in an elevated position within the valve chamber 5, and that the superior external fluid pressure will hold the valve element 15 in sealing-off engagement with the seat 14 so that none of the pressure fluid may get into 80 the well tubing. Suppose, now, that the liquid column slows in its movement so that the revamping element is permitted to settle back both by virtue of its own weight and by the action of the spring 21.

85 This settling of the revamping element will depress the plunger 15 from the seat 14 so that a little pressure fluid may enter, thus enlivening the liquid column and speeding the motion to what it ought to be. It is clear that a marked retardation of the liquid column will result in a pronounced opening of the valve element 15 so that volumes of 90 pressure fluid will be admitted quite in 95 agreement with the needs.

100 The reader will understand from what has been said before, that it is the velocity of the upwardly moving liquid column that regulates the admission of the lifting energy. The structure herein disclosed does 105 not depend for its operation directly upon differences of pressure inside and outside of the tubing for the admission of lifting energy as is the case in other applications, but depends upon the cause of this differential 110 for the actuating means, in other words, the 115 velocity of the upwardly moving liquid column.

An understanding of the foregoing principle is materially aided when it is borne in 120 mind that the liquid expansion chamber, previously designated as comprising the flared portions 18 and 20, provides for such action of the liquid as will induce a very faithful response of the revamping element. 125 The upwardly moving liquid, upon reaching this chamber, promptly expands and immediately again contracts when it reaches the diminishing throat leading up into the tube 17.

It is this peculiar manipulation of the liquid that has led to the term "revamping". The contraction or revamping of the moving liquid gives rise to a resistance which causes the revamping element 17 to be lifted when the velocity of such column has become properly accelerated.

As has been brought out already, this lifting of the revamping element removes the weight of the element from the stem 16, thus enabling the valve element 15 to engage and seal-off at the seat 14 provided the revamping element is lifted sufficiently high.

I claim:

1. Flowing apparatus comprising a shell having an internal enlargement providing a valve casing which has a passageway affording communication between the interior and exterior, a bushing fitted in the casing having a bore furnished with a valve seat, hollow inlet and outlet bushings in the ends of the shell the inlet bushing being flared, a valve element operable in the passageway having a portion to engage the seat and a stem extending through and beyond the bore, a revamping tube having a flare adjoining the flare of the inlet bushing to define a liquid expansion chamber the flare of the tube being guided within the shell, and a piston carried by the tube loosely guided within the shell and extending over the stem.

2. Flowing apparatus comprising a shell having an internal enlargement providing a valve casing which has a passageway affording communication between the interior and exterior, a bushing fitted in the passageway having a bore furnished with a valve seat, hollow inlet and outlet bushings in the ends of the shell the inlet bushing being flared, a valve element operable in the passageway having a portion to engage the seat and a stem extending through and beyond the bore, a revamping tube having a flare adjoining the flare of the inlet bushing to define a liquid expansion chamber, the flare of the tube being guided within the shell, a piston carried by the tube loosely guided within the shell and extending over the stem, and a spring interposed between the piston and the outlet bushing.

3. Flowing apparatus comprising a shell having a fluid passageway affording communication between the interior and exterior, means defining a rest near one end of the shell, a hollow weight loose in the shell one end of which weight is adapted to engage the rest, a piston on the other end of the weight, and a valve element operable in the passageway co-acting with the piston.

4. Flowing apparatus comprising a shell having an internal enlargement with a passageway affording communication between the interior and exterior, means in the shell defining a rest adjoining one end of the enlargement, a valve element operable in the

passageway and having a stem capable of protruding from the passageway into the shell at the other end of the enlargement, a hollow weight loose in the shell one end of which is adapted to engage the rest, and a piston on the other end of the weight occupying a position adjoining said other end of the enlargement and engageable with the valve stem.

5. Flowing apparatus comprising a shell having an internal enlargement with a passageway affording communication between the interior and exterior, means in the ends of the shell respectively defining a stop adjacent to the open end of the passageway and a rest adjacent to the other end of the enlargement, a valve element operable in the passageway having a stem capable of protruding through the open end, a hollow weight which at one end is adapted to engage the rest and which is movable in a zone between the rest and said other end of the enlargement, and a piston at the other end of the weight, co-acting with the valve stem and being movable in a zone between the stop and the open end of the passageway.

6. Flowing apparatus comprising a shell having a fixed bushing with a fluid bore laterally curved toward the interior of the shell and terminating in a rest, and a hollow weight loose within the shell, the major internal portion of the weight being cylindrical and having a frusto-conical flare the largest end of which is adapted to engage the rest to produce a liquid expansion chamber.

7. Flowing apparatus comprising a shell having a passageway with an open end communicating with the interior of the shell, a valve element operable in the passageway having a stem working through the open end, a hollow bushing having a portion cut away to define a chamber and a shoulder, a weight loose in the shell having a piston operable between the bushing and the open end of the passageway for engagement with said stem, and resilient means in the chamber abutting the shoulder and the piston.

Signed at San Antonio, in the county of Bexar and State of Texas, this 25th day of October A. D. 1927.
